UNITED STATES PATENT OFFICE.

STEPHEN C. RADFORD, OF OSHKOSH, WISCONSIN.

BUTTON.

1,096,643.

Specification of Letters Patent.

Patented May 12, 1914.

Application filed August 12, 1912. Serial No. 714,557.

To all whom it may concern:

Be it known that I, STEPHEN C. RADFORD, a citizen of the United States, and resident of Oshkosh, in the county of Winnebago and State of Wisconsin, have invented new and useful Improvements in Buttons, of which the following is a description, reference being had to the accompanying drawings, which are a part of this specification.

10 This invention relates to improvements in buttons.

It is one of the objects of this invention to provide a button which may be easily attached to and detached from a garment 15 without the necessity of sewing the button thereto.

A further object of the invention is to provide a detachable button which is simple in construction, strong and durable, and is 20 inexpensive to manufacture.

With the above and other objects in view, the invention consists of the improved detachable button and its parts and combinations, as set forth in the claims, and all 25 equivalents thereof.

In the accompanying drawing in which the same reference characters indicate the same parts in all of the views: Figure 1 is a front view of a fragment of two flaps of a 30 garment, with the improved button attached thereto, and as passed through the button hole of one flap thereof; Fig. 2 is a vertical central sectional view through the button and through the inner flap of the garment 35 to which the button is detachably connected; Fig. 3 is a detail view of the rear side of the button and also showing a small fragment of the inner flap of the garment; Fig. 4 is a view similar to Fig. 1 of a modified form 40 of button; Fig. 5 is a vertical sectional view thereof taken through the button and through the inner flap of the garment to which the button is detachably connected; Fig. 6 is a detail view of the rear side of the 45 button; and Fig. 7 is an edge view of another modified form of button shown attached to a piece of material, the material and a portion of the button being in section.

50 Referring to the drawing the numeral 8 indicates the main or body portion of the button, which on its inner side, and approximately medially thereof, is provided with a loop 9 which may be separate from and riveted to the button, as shown in the drawing, or may be integral with the button if preferred, said loop forming a tape

space between the button and the loop. The button, immediately above the loop, is provided with a semicircular slot 10, of a form approximating a shape of the letter C, to 60 form a tongue or lug 11 having a neck portion 12 of less width than the outer end portion.

A looped tape or other material 13, sewed at its ends to the inner flap portion 14 of 65 the garment, is adapted to have its looped portion extended through the button loop and over the tongue to secure the button to the inner flap portion. The button may now be used in the ordinary manner by 70 passing it through the button hole 15 of the outer flap 16 of the garment.

In the modified form shown in Figs. 4, 5 and 6 the button 17 is provided with a medially positioned opening or tape space 18 75 instead of the loop of the principal form, and through this opening is extended the tape loop 13 before described. Instead of forming the tongue integral with the button, as in the principal form, an independent 80 tongue 19 is provided which is riveted to the outer face of the button. The tape loop 13, which has been extended through the medial opening, is then passed over the tongue 19 and the button is thus secured to 85 the inner flap and may be used in the ordinary manner. I do not wish to be understood as confining this modified form to the tongue being located on the front or outer side of the button, inasmuch as results may 90 be secured by locating the tongue on the inner or rear side of a button of the principal form and eliminating the integral form of tongue, as clearly shown in Fig. 7. In this modified form the tongue is indicated by the numeral 19'. 95

While the device has been particularly described and claimed as a button, it is to be understood that the invention contemplates the use of the device for any purpose for 100 which it may be found adaptable and useful.

From the foregoing description it will be seen that the button is of very simple construction and may be easily detached from and attached to a garment when desired, 105 and is very desirable in use in connection with garments which have to be laundered.

What I claim as my invention is:

1. As an improved article of manufacture, a button provided with a tongue, a 110 loop fastened to one side of the button and positioned adjacent to the tongue, and a

2
looped tape extending through the loop and
detachably engaging the tongue.

2. As an improved article of manufacture,
5 projecting from one side of the button and
provided with a narrow neck portion, and
a tape extending through the tape space and
and detachably engaging the neck of the
tongue.

10 3. As an improved article of manufacture,
a button provided with a tape space in the

form of a loop on one of its sides, a tongue
fastened to one side of the button and posi-
tioned adjacent to the tape space, and a tape
loop extending through the tape space and 15
detachably extending over the tongue.

In testimony whereof, I affix my signa-
ture, in presence of two witnesses.

STEPHEN C. RADFORD.
